UNITED STATES PATENT OFFICE.

PHILIP KLEIN, OF BROOKLYN, NEW YORK, ASSIGNOR OF ONE-HALF TO MORRIS ROTH,
OF NEW YORK, N. Y.

OUTLET-BOX COVER.

1,283,804.

Specification of Letters Patent.

Patented Nov. 5, 1918.

Application filed December 13, 1917. Serial No. 206,928.

To all whom it may concern:

Be it known that I, PHILIP KLEIN, a citizen of the United States, and a resident of the city of New York, borough of Brooklyn, 5 in the county of Kings and State of New York, have invented a new and Improved Outlet-Box Cover, of which the following is a full, clear, and exact description.

This invention relates to electric wiring 10 attachment details and has particular reference to outlet boxes adapted for ceilings, walls, or the like.

Among the objects of the invention is to provide an improved type or design of outlet box cover having more reliable means for securing the cover to the box than is ordinarily employed. The means commonly used to secure a box cover to the box is of such a nature, one of several faults or difficulties is almost sure to exist. First, because of the inconvenience of operating at the ceiling it is a difficult expedient to connect the fastening means at such place. From this fact it follows that the connections are frequently faulty, leaving the cover insecurely attached, subject to coming loose or even dropping. Secondly, the fastening means as heretofore practised is of a nature tending to fracture or crack the cover rendering the 30 same unsafe from the underwriters standpoint.

To avoid the above and other objects I provide a cover for outlet boxes with peculiar means to secure it in place, said securing means being of the simplest possible form and because of the simplicity of the most reliable nature.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a vertical central sectional view showing my improvement applied to a ceiling for a drop light; and

Fig. 2 is a bottom plan view of the same, a portion of the cover being broken away.

Referring now more particularly to the 55 drawings, I show an outlet box 10 which *per se*

is or may be of any well known or approved construction and adapted to be secured to the ceiling or wall in permanent position by screws 11 or otherwise. Boxes of this type are usually constructed with a plurality of 60 holes 12 through which any desired number of wire cords 13 may extend. The box furthermore is usually provided with a central nipple 14, externally threaded, and having a central bore for a gas pipe connection. As 65 commonly practised the box may be flush with the outer surface of the plaster 15, or it may be above or below said surface, it not being infrequent for the box to be located as much as an inch or more within the surface 70 of the plaster.

16 indicates a box cover which *per se* is not materially different from box covers heretofore used, the same being designed as a neat ornamental closure device for the box and as 75 a means to inclose either the free ends of any idle wires 13, or the joints 17 between said wires and the cord 18 leading to the drop light or elsewhere. The cover is provided with a plurality of holes, one of which is 80 indicated at 19 in the center thereof and the other is indicated at 20 at one side of the center. The hole 19 is in axial alinement with the hole through the nipple 14 while the periphery or rim 21 of the cover is 85 adapted to seat directly upon the surface of the plaster or ceiling irrespective of the precise depth or location of the box with respect to said surface.

The reader's attention is now called to the 90 novel means for securing the cover to the box. This securing means comprises a cap 22 having direct threaded engagement with the outer end of the nipple and having an imperforate base or body serving as a closure for the hole through the nipple so that if the box is employed as a combination the cap constitutes a gas tight closure or plug. The cap is provided with a central boss 23 into which is tapped a hole 23' in 100 the axis of the hole 19, so that the hole 23' does not extend through the base or body of the cap. 24 indicates a finger piece indicated as in the nature of a rosette of a somewhat ornamental appearance, but adapted 105 to be manipulated conveniently with one's fingers for securing it in place or removing it. The finger piece has a hub portion 25 having a central hole tapped to accommodate one end of a screw 26, the other end of 110

the screw having threaded engagement in the hole 23'. The screw 26 may be provided of any desired length, as much as two or three inches in practice, so that it will 5 reach and engage with the cap 22 irrespective of the depth of the box within the surface of the ceiling or wall. The operator in making his connections applies the cap to the nipple 14 and then determines the 10 proper length for the screw 26. When this is determined he clips off the screw at the proper length and screws it either into the finger piece 24 or else into the cap boss 23, in position to make final connection with 15 the other part with the cover in place and with the cord 18 passing through the hole 20. When the finger piece is then rotated the screw will be securely fixed in both parts 23 and 25 and the cover will be clamped 20 firmly in place making a neat and effective closure for the box. It will thus be seen that the means for connecting the cover to the box will be positive and easily applied irrespective of the distance between the box 25 and the cover. Furthermore it is obvious that the cover may easily be disconnected when desired by simply unscrewing the finger piece. The hub 25 fits into the central hole 19 of the cover and keeps the cover 30 well centered even though the rim 21 of the cover may be remote from the outer edge or rim of the box.

Copies of this patent may be obtained for five cents each, by addressing the "Commissioner of Patents, Washington, D. C."

It will be noted that the screw 26 when fixed in place firmly by the finger piece 24 will so hold the cover 16 that there can be 35 no vibration or wiggling of the cover even though the weight of the drop light may be borne upon it. When the splicing of the wires is effected and the joint or joints are inclosed by the cover 16 and the cover is 40 locked in place as already described there can be no danger of any metallic connections that would cause any short circuit or ground such as is so likely to occur in box covers now in common use where the cover-holding 45 screws must be passed into place through the space in which the splice or splices lie.

I claim:

The combination with an outlet box having a projecting tubular nipple and a cover having a hole in axial alinement with said nipple, of connecting means between the box and cover comprising a cap secured to the end of the nipple and serving as a closure for the same, said cap having a hole tapped into and partially through the same in axial alinement with the cover hole, a finger piece having a smooth hub journaled in the cover, said hub having a tapped hole therein in alinement with the cap hole, and a screw of selective length having its ends fitted in said cap hole and finger piece respectively.

PHILIP KLEIN.
